DESIGN FOR A PIPE REAMER FOR PIPE THREADING TOOLS

Carl H. Ingwer and Clyde E. Wright, Elyria, Ohio

Application July 21, 1937, Serial No. 70,563

Term of patent 14 years

To all whom it may concern:

Be it known that we, Carl H. Ingwer and Clyde E. Wright, citizens of the United States and residents of Elyria, in the county of Lorain and State of Ohio, have invented a new, original, and ornamental Design for a Pipe Reamer for Pipe Threading Tools, of which the following is a specification, reference being had to the accompanying drawing, forming a part thereof.

Figure 1 is a top plan view of a pipe reamer for pipe threading tools showing our design; and
Figure 2 is a side elevational view thereof.

We claim:

The ornamental design for a pipe reamer for pipe threading tools, substantially as shown.

CARL H. INGWER.
CLYDE E. WRIGHT.
